CLAIM

The ornamental design for a chandelier, as shown and described.

DESCRIPTION

FIG. 1 is a top, front and right-side perspective view of the chandelier showing my new design;

FIG. 2 is a bottom, rear and left-side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view, of circled portion 9, of FIG. 1, thereof;

FIG. 10 is an enlarged view, of circled portion 10, of FIG. 1, thereof;

FIG. 11 is an enlarged view, of circled portion 11, of FIG. 1, thereof;

FIG. 12 is an enlarged view, of circled portion 12, of FIG. 1, thereof;

FIG. 13 is an enlarged view, of circled portion 13, of FIG. 1 thereof;

FIG. 14 is an enlarged view, of circled portion 14, of FIG. 1 thereof;

FIG. 15 is an enlarged view, of circled portion 15, of FIG. 3 thereof;

FIG. 16 is an enlarged view, of circled portion 16, of FIG. 1 thereof;

FIG. 17 is an enlarged view, of circled portion 17, of FIG. 7 thereof; and,

FIG. 18 is an enlarged view, of circled portion 18, of FIG. 2 thereof.

The dot-dash broken lines depict the boundaries of the FIGS. 1-3, 7 and 9-18 enlargement that forms no part of the claimed design.

1 Claim, 18 Drawing Sheets
